(57) CLAIM

The ornamental design for a tank top, as shown and described.

DESCRIPTION

FIG. 1 is a front view of the tank top, showing my new design;

FIG. 2 is a rear view thereof;

FIG. 3 is a right side view thereof;

FIG. 4 is a left side view thereof;

FIG. 5 is a top view thereof;

FIG. 6 is a top view inside out thereof;

FIG. 7 is a front view as shown on a person thereof;

FIG. 8 is a right side view as shown on a person thereof;

FIG. 9 is a rear view as shown on a person thereof;

FIG. 10 is a front view, where the front of the tank top as displayed in FIG. 1 is worn as the rear and the rear as displayed in FIG. 2 is worn as the front, as shown on a person thereof;

FIG. 11 is a side view, where the front of the tank top as displayed in FIG. 1 is worn as the rear and the rear as displayed in FIG. 2 is worn as the front, as shown on a person thereof; and,

FIG. 12 is a rear view, where the front of the tank top as displayed in FIG. 1 is worn as the rear and the rear as displayed in FIG. 2 is worn as the front, as shown on a person thereof.
